UNITED STATES PATENT OFFICE.

JOHN C. McDONALD, OF NEW YORK, N. Y.

RAILWAY-TRAIN-CONTROLLING SYSTEM.

1,151,025.

Specification of Letters Patent. Patented Aug. 24, 1915.

Application filed October 9, 1911, Serial No. 653,477. Renewed January 21, 1915. Serial No. 3,629.

To all whom it may concern:

Be it known that I, JOHN C. McDONALD, a citizen of the United States, and a resident of New York, in the county of New York and State of New York, have invented certain new and useful Improvements in Railway-Train-Controlling Systems, of which the following is a specification.

10 My invention relates to improvements in railway block systems and combined block and signal systems, and comprises means whereby power is cut off from a motor car or train seeking to enter a block already occupied, also electromagnetic switches of a simple type, preferably operated by track circuits, controlling the supply of current to the several block sections, also simple signal circuits whereby both danger and caution signals are provided.

15 The objects of my invention are to facilitate the operation of railways, to reduce the danger of collisions, to provide improved and simplified means for cutting off the power from a motor car or train seeking to enter a block already occupied, and to provide improved and simplified signal circuits.

20 I will now proceed to describe my invention with reference to the accompanying drawings, in which—

Figure 1 is a diagrammatic view showing the circuits and switches of one track of a double track electric railway system embodying my invention, the direction of normal progress along such track being indicated by an arrow. Fig. 2 is a side view and Fig. 3 an end view of one of the switches employed in my system. Figs. 4-9 inclusive are detail views of contact mechanism of such switch, Figs. 4, 5 and 6 showing the parts in their normal position and Figs. 7, 8 and 9 showing said parts in their abnormal or danger position. Figs. 5 and 8 are transverse sections of the oscillatory barrel of the switch; Figs. 4 and 7 are longitudinal sections of said barrel, looking from the right of the center; Figs. 6 and 9 are similar sections of the barrel looking from the left of the center.

According to my invention current is communicated to the motors of a car or train on the track through a sectional conductor having as many sections as there are blocks; which conductor may conveniently be a third rail, though it might also be a

trolley wire. To each section of such conductor current is communicated from a feed wire through a suitable switch controlled by track circuits; to which end one of the 60 track rails is divided into as many insulated sections as there are blocks, the other rail (which is a ground or return rail) not being so divided. The switch which I prefer to employ is a mercurial switch operated by an electromagnet, each such magnet being controlled by one of the track circuits.

Referring first to Fig. 1, T represents the track rail which is not divided into block sections, and T¹, T², etc., designate block sections of the other track rail. R¹, R², etc., designate corresponding sections of the current supply conductor. It will be observed that the several sections of the current supply conductor are not coterminous with the corresponding sections of the track rail T¹, T², etc., but that the power rail sections R¹, R², etc., each extend a short distance into the succeeding block. The reason for this will be explained presently. Current is supplied to the various power rail sections, R¹, R², R³, etc., through a feed conductor F, and through switches S¹, S², etc., and conductors 17, there being one such switch for each block. Without limiting myself to any particular variety of switch I will state that I prefer a mercurial contact switch of the construction illustrated in Figs. 2-9 inclusive and comprising an oscillatory barrel 1, constructed to contain mercury or other 90 suitable fluid conductor, and pivoted on an axis 2 somewhat above the geometric center of the drum 1. The switch further comprises an arm 3 connected to such barrel 1, an electromagnet 4, an armature 5, for moving the barrel in one direction (the magnet and armature illustrated being of the solenoid and plunger type) and a retractile spring 6. The barrel 1 is customarily provided internally with a layer of mercury 7, of suitable depth; and to keep the surface of this mercury clean, and also to reduce evaporation, and prevent sparking, the surface of the mercury may be covered with a layer 8, of oil or the like, of suitable depth; such oil being a good insulator. The barrel 1 is further provided with two sets of contact points, one set being numbered 9 and 10, the other set being numbered 11 and 12. It will be understood that the drum 1 is 100 constructed of some non-conducting material, so that the contact pieces 9-12 inclusive

are insulated from each other except as they dip into the mercury, or that other suitable means are employed to insulate the contact pieces one from another. The location of the various contact points is such that contacts 9 and 10 are immersed in the mercury when the switch barrel 1 is in its normal position; the contacts 11 and 12 being then out of the mercury; and that when the switch barrel is in its abnormal position, produced by energization of the magnet 4, contacts 11 and 12 will be immersed in the mercury and contacts 9 and 10 will be out of the mercury and therefore insulated from one another.

Referring now again to Fig. 1, and considering the circuits of the system, the circuit of the switch magnet 4 of each block is controlled by the track circuit of that block and also by the contact points of a switch of one of the blocks beyond. Customarily it is considered sufficient to maintain a train-interval of not more than two blocks, between trains, and therefore in Fig. 1 I have shown the circuit of each switch magnet 4 controlled by the contact points of a switch two blocks ahead; but it will be obvious that the circuit of the switch magnets might be controlled by the contacts of switches either a less number of blocks or a greater number of blocks ahead. Considering now the switch-operating circuit of one of the blocks, block T^1 for example, 13 designates a circuit conductor connected to rail section T^1 and passing through magnet 4 of switch S^1 and thence passing to contacts 10 of switch S^3 . From contact 9 of said switch, a conductor 14 passes to a common return conductor 15 and thence to one pole of a switch-operating generator 16, the other pole of which is grounded. Rail T being grounded, it will be apparent that when a car or train enters block T^1 the wheels of such car or train will complete the track circuit from T to T^1 , thereby completing circuit from the grounded side of the battery 16, through rail T , the wheels and axles of the train, the rail T^1 and magnet 4 of switch S^1 , to contact 10 of switch S^3 . If switch S^3 is in its normal position, as it will be if block T^3 is not occupied, this circuit will further be completed from contact point 10 through the mercury of switch S^3 to contact 9 to conductor 14 and thence through conductor 15 back to battery 16. The completion of this circuit will energize magnet 4, causing said magnet to swing the switch barrel S^1 to one side, and thereby operating certain signal circuits as well as protecting the train from other trains in rear, as will be described presently, and also connecting rail R^1 , to feed wire F. Supposing, however, that the block T^3 is occupied when a train enters block T^1 . In such case, since the track circuit of block T^3 passing through magnet 4

of switch S^3 of that block, is completed through the wheels and axles of the car or train of the block T^3 , switch S^3 will be in its abnormal or operating position, when the second train seeks to enter block T^1 , and therefore the barrel of switch S^3 will be in its abnormal position, indicated in Figs. 7, 8 and 9, contacts 9 and 10 of switch S^3 will be insulated from one another, and contacts 11 and 12 of switch S^3 will be connected through the mercury of switch S^3 . The function of these contacts 11 and 12 will be described presently. Since, with block T^3 occupied, the train entering block T^1 cannot complete the circuit through the magnet 4 of switch S^1 , because such circuit is broken at contacts 9 and 10 of switch S^3 , it follows that the train entering block T^1 can receive no current from power conductor section R^1 , and therefore the train entering block T^1 must come to rest shortly after entering that block, and must remain at rest until block T^3 is no longer occupied. As soon as the car or train of the block T^3 passes out of that block, the barrel of the switch S^3 will return to normal position by gravity, and thereupon the track circuit of magnet 4 of switch S^1 of block T^1 will be completed through contacts 9 and 10 of switch S^3 , and the train in block T^1 may proceed. The sections R^1 , R^2 , etc., of the power rail overlap somewhat the corresponding sections T^1 , T^2 of the sectional track rail, in order that a train seeking to enter a block may enter that block sufficiently to complete the track circuit of that block, if the second block ahead is unoccupied, and to permit the motorman to bring his train to rest if the signals at the entrance of the block so require; it being of course desirable that the motorman may be able to bring his train to rest before passing on to the dead section of the power rail, so that the entering train may retain power to move backward, if necessary.

With the sectional power conductor system above described, I preferably combine a signal system, the circuits of which are controlled by the same switches which control the power circuits. The contacts 11 and 12 of each switch are signal-circuit contacts. Considering the signal circuits of the block T^3 , it will be seen that when contacts 11 and 12 of switch S^3 are connected through the mercury of that switch, not only is the power circuit complete from feed wire F to contacts 12 and 11, of switch S^3 , and wire 17 to power conductor section R^3 , but also a signal circuit is complete from feed wire F through contacts 12 and 11, and signal wire 18 to a danger signal D of the preceding block and to a caution signal C of block T^1 . These danger and caution signals may be of any suitable construction; but I have indicated electric lamps for the purpose. As is customary in ordinary railway

work, where lamps or the like are used for signals, the danger signal lamps will be of one color and the caution signal lamps will be of another color. In the drawings I have indicated the danger signal lamps by the symbol $\bigcirc$ and the caution signal lamps by the symbol $\otimes$. It will be seen therefore that when a car or train seeks to enter a block R^1 for example, when the second block 10 ahead is occupied, the motorman will find the caution lamps of the block which he is seeking to enter, lighted, and will thereby be notified to bring his train to rest before entering the dead rail section R^1 . Should 15 the train in block T^3 leave that block by backing into block T^2 , then as soon as such train enters block T^2 and before it has left block T^3 , it will actuate switch S^2 and thereby will illuminate the danger signal lamps 20 D of block T^1 ; so that notwithstanding when such train of the block T^3 has passed entirely from block T^3 to T^2 and so has permitted operation of switch S^1 , the train seeking to enter block T^1 will be debarred 25 from proceeding on in that block, by the danger signal D .

What I claim is:—

1. A railway train-controlling system, comprising in combination a power conductor divided into sections, means for supplying current to the several sections of said conductor, comprising an electrically-controlled switch for each such section, and track circuits including means for operating 30 said switches, the track circuit for each such switch passing through a contact of a switch of a section in advance which contact is closed when said advance switch is in normal or clear position and is broken when 35 such advance switch is in the abnormal or danger position.

2. A railway train-controlling system, comprising in combination a power conductor divided into sections, means for supplying current to the several sections of 40 such conductor, comprising an electrically- 45

controlled mercurial switch for each such section, and circuits, arranged to be operated by a passing car, said circuit including means for operating said switches, the circuit for operating each such switch passing through a contact of a switch of a section in advance which contact is closed when said advance switch is in normal or clear position and is broken when such advance switch 50 is in abnormal or danger position.

3. A railway train-controlling system, comprising in combination a power conductor divided into sections, means for supplying current to the several sections of said conductor, comprising an electrically-controlled switch for each such section, and track circuits including means for operating said switches comprising track rails one of which is divided into insulated block sections each corresponding generally to one of the sections of the power conductor, but not coterminous therewith; each section of the power conductor extending somewhat into the block in advance. 55

4. A railway train-controlling system, comprising in combination a power conductor divided into sections, means for supplying current to the several sections of said conductor comprising an electrically controlled switch for each such section, track circuits including means for operating said switches, the circuit for operating each such switch passing through a contact of a section in advance, which contact is closed 60 when such advance switch is in normal or clear position, and is broken when such advance switch is in abnormal or danger position, and a signal circuit likewise operated by such switch. 65

In testimony whereof I have signed this specification in the presence of two subscribing witnesses.
